PORTABLE APPARATUS FOR BALING TRASH
Sterl F. Taylor, Oxnard, Calif.; Ethel M. Taylor, Oxnard, Calif., executrix of said Sterl F. Taylor, deceased, assignor, by mesne assignments, to Tamaker Corp., a corporation of California

Filed Mar. 1, 1963, Ser. No. 262,987

2 Claims. (Cl. 100—74)

This invention relates generally to the baling of trash and more particularly to an improved portable apparatus for facilitating baling of trash directly at trash sites.

Conventional trash equipment for forming bales of trash is usually located at a permanent site and the trash brought to the baling apparatus from various locations in trucks. In baling the trash, relatively complex equipment has been employed to compress the same into a given sized bale for easy storage or subsequent re-use by paper product mills and the like.

With the above in mind, it is a primary object of this invention to provide a novel portable apparatus for baling trash, in which the apparatus may be driven directly to a trash site and trash loaded therein and compressed into suitable bales of standard size.

More particularly, it is an object to provide an improved portable apparatus for baling trash particularly adaptable to waste paper, cardboard, and the like to form compressed bales at a trash site which may subsequently be loaded onto commercial vehicles for transportation to any desired location to the end that the immediate disposal of trash is greatly facilitated.

Still another important object is to provide a portable apparatus for baling trash meeting the foregoing objects which is rugged in construction, economical to operate, and may easily be transported to any desired site by conventional commercial vehicles.

Briefly, these and further objects and advantages of this invention are attained by providing a basic frame structure having wheels to facilitate the portability of the structure. A trash receiving enclosure is mounted on the frame structure and includes compressing means within the enclosure so that trash received within the enclosure may be dispensed therefrom in compressed form and in a regulation sized bale.

The invention thus contemplates the steps of loading trash into an enclosure; moistening the trash; compressing the trash to a smaller volume in the enclosure; loading additional trash into the enclosure; moistening the additional trash; compressing the additional trash against the first mentioned trash; repeating the last mentioned three steps a plurality of times until a compressed bale of trash of given volume is formed; and then unloading the compressed bale of trash from the enclosure. The moistening step serves to "bind" the material together and cause it to adhere in a given compressed shape corresponding to a commercial bale.

The preferred apparatus includes an enclosure and compressing means within the enclosure as described. Preferably, hydraulic means are employed for effecting the compressing operation. The enclosure itself includes a lower front gate and upper rear gate and incorporates a platform adapted to be raised between lower and upper positions to effect the compressing operation. By this arrangement, trash may readily be loaded into the lower front gate from a trash site without having to raise the trash beyond a minimum distance. On the other hand, when the same has been compressed by raising of the platform to squeeze the trash against the ceiling of the enclosure, the completed bale is disposed at a higher level and when removed through the rear gate is in a proper position for reception directly onto a commercial vehicle for subsequent transportation.

2

Various features of novelty in the portable apparatus include the arrangement of hydraulic units for actuating the system and the provision of unique means for enabling the trash to be compressed against the ceiling of the enclosure as well as unique means for facilitating the unloading of a completed bale.

The foregoing will be better understood by now referring to a preferred embodiment of the invention as disclosed in the accompanying drawings, in which:

FIGURE 1 is an overall perspective view of the portable apparatus for baling trash in accordance with the invention;

FIGURE 2 is a fragmentary cross sectional front view taken generally in the direction of the arrows 2—2 of FIGURE 1;

FIGURE 3 is a side view partly in cross section taken generally in the direction of the arrow 3 of FIGURE 1;

FIGURE 4 is an enlarged fragmentary cross section of a portion of the structure of FIGURE 3 enclosed within the circular arrow 4; and

FIGURE 5 is a schematic diagram illustrating the hydraulic circuits for operating the various components of the structure illustrated in FIGURES 1-3.

Referring first to the lower portion of FIGURE 1, there is illustrated a basic frame structure 10 having wheels 11 for rendering the structure portable. As shown, the frame structure supports a trash receiving enclosure 12 generally of box shape. This enclosure includes front and rear walls 13 and 14, sidewalls 15 and 16, a lower floor or bottom wall 17 and a top wall or ceiling 18.

A portion of the front wall 13 includes a front gate 19 mounted for swinging movement at 19' along the lower front longitudinal edge of the bottom wall 17. The rear wall 14 in turn includes a rear gate 20 which is mounted for swinging movement along the upper rear longitudinal edge of the top wall 18 as at 20'. Included within the enclosure is a platform 21.

With particular reference to FIGURE 2, there are provided platform raising and lowering means for the platform 21 in the form of a pair of hydraulic cylinders 22 and 23 secured to the frame structure on opposite sides of the enclosure 12. As shown, these cylinders include piston rods 24 and 25 coupled at their upper ends to pull rods 26 and 27. The lower ends of the pull rods in turn connect to opposite sides of the platform 21. The sidewalls 15 and 16, as best shown in FIGURE 1, include elongated slotted open portions for accommodating the upper ends of the pull rods 26 and 27. Guiding means for the upper ends of the piston rods 24 and 25 in the form of angle irons such as indicated at 28 and 29 are provided and extend a considerable distance above the top wall 18 of the enclosure. The arrangement is such that actuation of the hydraulic cylinders 22 and 23 will serve to raise the platform 21 from a lower position juxtaposed the front gate 19 to an upper position juxtaposed the rear gate 20.

Referring to the side cross sectional view of FIGURE 3, the front gate 19 is arranged to be actuated by a hydraulic cylinder 30 disposed beneath the frame structure 10. This cylinder 30 is mounted for swinging movement and includes a front projecting piston rod 31 coupled to a suitable push bar 32 in turn rigidly secured to the front gate 19. Outward movement of the piston rod 31 will serve to close the front gate 18 whereas retracting movement thereof will serve to open this gate.

Similarly, the rear gate 20 is arranged to be actuated by a hydraulic cylinder 33 disposed along the top wall 18 of the enclosure. As shown in both FIGURES 1 and 3, this cylinder 33 actuates the rear gate 20 through the medium of a flexible cable 34 secured to a rigid bar 35 extending normally from the plane of the rear gate 20. The cable then passes about a pulley 36 and is secured

to the front of a piston rod 37 projecting from the cylinder 33. Hydraulic actuation of the cylinder 33 will thus serve to open the rear gate 20.

Referring once again to FIGURE 3, there is provided an unloading structure including a hydraulic cylinder 38 mounted to the upper end of the box-like enclosure and having a piston rod 39 projecting towards the front wall 13. This front wall 13 includes a key hole type slot 40 through which the piston rod 39 for the cylinder 38 projects. Actuation of the hydraulic cylinder 38 will extend the piston rod 39 to push a bale 41 of trash from the upper portion of the enclosure through the rear gate 20.

In accordance with one feature of this invention, the upper interior corner portions of the rear gate 20 include rigid bars 42 extending normally from the plane of the gate so that when the gate 20 is swung outwardly, the bars 42 will swing downwardly to bear against the upper surface of the bale 41 and tilt the same to facilitate its removal from the enclosure.

As shown in FIGURE 3, the frame 10 also serves to support a source of hydraulic fluid 43 cooperating with a hydraulic pump 43' for supplying hydraulic fluid under pressure to the various cylinders. By this arrangement, the unit is entirely self-contained.

In accordance with a further feature of the apparatus, there is provided means for moistening trash received through the front gate 19. This means takes the form of a header pipe 44 also shown in FIGURE 1 arranged to receive water under pressure from a suitable pump (not shown) connected to a water tank 45 disposed beneath the front gate structure 19 as shown in FIGURE 3. The same drive for the hydraulic pump 43' may be used to drive the water pump for pumping spray water from tank 45. By moistening trash received through the front gate, preparatory to its being raised by the platform 21 to form a bale, the trash will tend to adhere together and "bind" more easily.

As will be evident from the front view of FIGURE 2 and the side view of FIGURE 3, the front and rear walls 13 and 14 include a plurality of elements 46 pivoted thereto. With particular reference to the enlarged fragmentary cross section of FIGURE 4, one such element 46 is shown pivoted at 47 to a slot portion in the front wall 13. The wall is shaped such that the element 46 may swing from a horizontal position generally upwardly towards a vertical position to lie substantially co-planar with the wall. However, the element 46 is locked against downward swinging movement beyond a horizontal position by a stop structure 48 abutting the rear end of the element to the left of the pivot 47 as viewed in FIGURE 4. By this arrangement, when trash is raised by the platform 21, it will push past the elements 46 swinging them upwardly as indicated in dotted lines in FIGURE 4. When the trash has passed the elements, they will fall to their horizontal positions by gravity and thus engage under the trash that has been raised so that the platform 21 may be lowered preparatory to receiving additional trash.

Referring now to FIGURE 5, there is illustrated a simple schematic diagram of the interconnections between the various cylinders described in conjunction with FIGURES 1-3. As shown, the source 43 and pump 43' provide hydraulic fluid under pressure along a first line 49 to a hand operated valve 50. From the valve 50, the fluid under pressure passes to a four-way valve 51. Depending upon the position of this four-way valve 51, hydraulic fluid under pressure can be provided on output line 52 or 53. When provided on output line 52, the fluid will pass to the lower ends of the cylinders 22 and 23 to raise the pistons therein, fluid above these pistons then passing out the line 54. The fluid in the line 54 then passes down line 53 which functions as a return line when the four-way valve is in the position described, the return fluid passing through a line 55 to the reservoir 43.

If the four-way valve is moved in the opposite direction, high pressure will be provided on the line 53, and the

line 52 will be connected to the line 55 so that high pressure passes into the line 54 to the upper ends of the cylinders to lower the pistons, fluid from the lower ends of the cylinders passing through line 52 to line 55.

As also shown in FIGURE 5, the front gate cylinder 30 is arranged to be operated by hydraulic fluid pressure in the line 52 through a branch line 56 passing through a hand valve 57. When the piston from the cylinder 30 is extended as by high pressure passing through the valve, the front gate will be closed. This action may take place substantially simultaneously as the lift cylinders commence operation; that is, when high pressure is on the line 52 from the four-way valve 51. On the other hand, when it is desired to retract the cylinders and open the front gate preparatory to receiving further trash, high pressure on the line 53 will be passed through a branch line 57' to the other end of the cylinder 30 to retract the piston rod therein. Return fluid from the right hand end of the cylinder 30 will then pass through the valve 57, and line 52, to the return line 55.

The rear gate cylinder 33 shown in the lower left-hand corner of FIGURE 5 in turn is arranged to be actuated by high pressure fluid from the pump 43' passing through a branch line 59 and a hand valve 60. This fluid enters a four-way valve 61 similar to the valve 51 which is capable of providing high pressure on either one of two output lines 62 or 63. When pressure is applied to output line 62, the piston for the cylinder 33 is extended to open the rear gate. When high pressure is provided on the line 63, the piston in the cylinder 33 will retract permitting the rear gate to close.

Cooperating with this same four-way valve 61 is the cylinder 38 for ejecting the bale as described in conjunction with FIGURE 3. This cylinder may be operated to push the bale from the upper portion of the enclosure at the same time that the rear gate cylinder 33 is operated, and towards this end, there is provided a branch line 64 passing through a hand valve 65 to the righthand end of the cylinder 38.

When the rear gate is retracted or closed, the fluid passing through the line 63 also passes to the left end of the cylinder 38 to retract the piston rod 39 preparatory to the formation of another bale.

From the foregoing description, the operation of the overall system will be evident. Initially, and with reference to FIGURE 3, the rear gate 20 is closed and the front gate 19 swung open by operation of the hydraulic cylinder 30. Further, the platform 21 is in its lowermost position as shown in dotted lines in FIGURE 3. Under such conditions, trash directly from a trash site readily may be loaded onto the platform 21 and this job may be carried out very easily since the platform level is relatively low as compared with the rest of the structure. When a certain amount of trash has been inserted through the front gate, the front gate 19 is swung closed by actuation of the hydraulic cylinder 30. Simultaneously, water from the spray header pipe 44 may be ejected to moisten the trash.

As the gate 19 is being closed, the lift cylinders 22 and 23 may be actuated through the high pressure line 52 from the four-way valve 51 described in FIGURE 5 to raise the platform 21. The trash will thus be compressed against the top wall 18 of the enclosure, and as the trash passes the various elements 46 pivoted to the front and rear walls, these elements will be retracted and then by gravity fall to horizontal positions to engage under the edges of the compressed trash.

After the trash has been initially compressed, the platform is lowered with the rear gate 20 held closed and the front gate 19 again opened to receive further trash. This further trash is then raised and compressed against the trash already being held in the upper portion of the enclosure by the elements 46. The additional trash supplied to the platform is moistened by water from the header pipe 44 so that it will adhere together and be com-

pressed into a solid mass with the first trash already disposed in the upper portion of the enclosure.

The foregoing process may be repeated a plurality of times until a relatively large bale is formed in the upper portion of the enclosure. When it appears that further compression is not feasible because of the mass of trash present in the upper end of the enclosure, the rear gate 20 may be actuated and at the same time the cylinder 38 operated to extend the piston 39 and urge the bale 41 shown in FIGURE 3 from the upper portion of the enclosure. In this connection, opening of the rear gate 20 will cause the bars 42 to engage the upper top portions of the bale 41 to tilt the same as illustrated and thus facilitate its removal from the enclosure.

Since the rear gate portion of the enclosure is at a higher level than the front gate portion, commercial type trucks having rear platforms may be positioned substantially level with the rear of the machine of FIGURE 3 so that the bale may be received directly thereon. Thus, an important feature of this invention resides in the fact that during the compression operation, the mass of trash is actually raised to a higher level to facilitate loading onto commercial type trucks.

After the bale 41 has been removed from the upper end of the enclosure as illustrated in FIGURE 3, the rear gate is closed and the platform 21 lowered and the front gate 19 opened preparatory to receiving further trash. The various plurality of compression and moistening steps are repeated until another bale is formed and this latter bale is then ejected in the manner described for the bale 41.

From the foregoing description, it will thus be evident that the present invention has provided a greatly improved portable type apparatus for baling trash. While only certain components in the apparatus have been shown and described in accordance with one embodiment of applicant's invention, it will be evident that equivalent steps and components could be substituted without departing from the scope and spirit of this invention. The improved portable apparatus for baling trash is therefore not to be thought of as limited to the exact embodiment set forth merely for illustrative purposes.

What is claimed is:

1. A portable trash baling apparatus comprising, in combination: a frame, a trash receiving enclosure mounted on said frame and having a lower front gate hinged along the lower front longitudinal edge of said enclosure for swinging movement outwardly and downwardly and an upper rear gate hinged along the upper rear longitudinal edge of said enclosure for swinging movement outwardly and upwardly; a rear gate actuating hydraulic cylinder and piston means connected to said rear gate for opening and closing the same; a movable platform in said enclosure; a pair of platform raising and lowering hydraulic cylinders mounted on said frame adjacent to said enclosure in vertical positions; piston rods adapted to be raised and lowered from ends of said cylinders; rod means connecting the upper ends of said piston

rods to opposite side portions of said platform for moving said platform from a lower position in said enclosure juxtaposed to said front gate to an upper position in said enclosure juxtaposed to said rear gate whereby trash may be received on said platform through said lower front gate when said platform is in its lower position, compressed into a bale when said platform is raised to its upper position, and disposed of through said rear gate while said platform is in its upper position; means on said enclosure for moistening said trash after it is received through said front gate preparatory to being compressed; an unloading hydraulic cylinder and piston positioned exteriorly of said enclosure in a direction facing a front wall of said enclosure above said front gate, said front wall including a slot opening for receiving a piston rod projecting from said cylinder whereby actuation of said cylinder projects said piston rod into said enclosure to urge said trash bale past said rear gate free of said enclosure after opening of said rear gate; a source of hydraulic fluid connected to said rear gate actuating cylinder, pair of platform raising and lowering cylinders, and said unloading cylinder; and control means for selectively actuating said cylinders.

2. An apparatus according to claim 1, in which said enclosure is generally box-shaped having front and rear walls formed in part by said front and rear gates when closed, sidewalls, and top and bottom walls, said front and rear walls including a plurality of rotatable lever elements swingable from horizontal positions, in which ends of said elements project inwardly into said enclosure, towards vertical positions in which said ends are directed upwardly so that said elements lie substantially in the planes of said walls, whereby trash raised on said platform past said elements swings said elements towards their vertical positions until said trash is past said elements, at least some of said elements dropping back to their horizontal positions by gravity so that said ends support said trash in its raised position after being compressed while said platform is lowered preparatory to receiving additional trash.
